(57) **CLAIM**

We claim the ornamental design for a display screen with graphical user interface, substantially as shown and described.

DESCRIPTION

FIG. 1 is a front view of a display screen with graphical user interface showing our design; and,

FIG. 2 is a front view thereof, shown in an alternate environment.

The broken lines shown in the drawings represent the display screen and the remainder of the graphical user interface and form no part of the claimed design.
